UNITED STATES PATENT OFFICE.

FRANK A. NIEBERDING, OF CLEVELAND, OHIO.

STOVE.

1,184,865.

Specification of Letters Patent.

Patented May 30, 1916.

Application filed March 14, 1913. Serial No. 754,276.

To all whom it may concern:

Be it known that I, FRANK A. NIEBERDING, a citizen of the United States, residing at Cleveland, in the county of Cuyahoga and State of Ohio, have invented a certain new and useful Improvement in Stoves, of which the following is a full, clear, and exact description, reference being had to the accompanying drawings.

10 This invention relates to stoves or ranges which are used for cooking and baking, and particularly to that type of such stoves or ranges wherein either solid fuel or gas may be burned, as desired. In prevailing stoves 15 of this type with which I am familiar, the parts required for the burning of one kind of fuel interfere, more or less, with the successful operation of the stove when the other kind of fuel is used. This is especially true 20 as regards the ovens, the efficiency of which is reduced when solid fuel is used by the presence of the gas-burning equipment therebeneath. Moreover, in some of these 25 stoves it requires the removal of certain pieces and the insertion of other parts in order to transform the stove from one burning solid fuel to one in which gas is burned, and vice versa.

It is the object of my invention to provide 30 a stove of this character which is highly efficient; which can be converted from a solid fuel stove to a gas stove by simply inserting a deflector in the bottom of the oven, and which is immediately restored to a solid 35 fuel stove by the removal of the deflector; wherein the parts required for the burning of one kind of fuel do not lessen the efficiency of the stove when the other kind of fuel is used; and in which air is supplied to 40 the oven burner automatically upon the operation of the gas valve and in proper proportion to the quantity of gas which issues therefrom.

Generally speaking, my invention may be 45 defined as consisting of the combinations of elements set forth in the claims annexed hereto and illustrated in the accompanying drawings forming a part hereof, wherein:

Figure 1 is a sectional view of my improved stove or range, the section being taken on the line 1—1 of Fig. 3; Fig. 2 is a sectional view of the stove at right angles to Fig. 1 and corresponding to the line 2—2

of said figure; Fig. 3 is a plan view of the stove, a portion of the top plate being broken away; Fig. 4 is a sectional detail taken on the line 4—4 of Fig. 1 and showing the oven vent and the means for automatically operating the damper therefor; Fig. 5, a sectional detail of the oven burner, the view being taken vertically through the oven burner chamber on the line 5—5 of Fig. 1; Fig. 6 represents a horizontal section through said chamber taken substantially on the line 6—6 of Fig. 5 and showing the damper which automatically controls the supply of air thereto; and Fig. 7, a view similar to Fig. 6, and illustrating a modified form of the damper.

Like reference characters designate corresponding parts throughout the several views of the drawing.

Mounted upon the base 1 is the casing of the stove, which comprises generally a rectangular bottom plate or wall 2, end walls 3 and 4, a front wall 5, a rear wall 6, and a top plate 7. These parts may be joined in any approved manner, common to the class of work to which this invention relates.

A partition or wall 8, which extends from the front wall 5 to the rear wall 6 of the casing, rests upon the bottom plate or wall 2 and projects upwardly to within a short distance of the top plate 7. A plate 9, which is of the same width as the partition 8, joins the top edge thereof at right angles and extends horizontally therefrom to within approximately the same distance from the end wall 4 as the top of the partition 8 is spaced from the top plate 7. A plate 10, which is of substantially the same area as the plate 9, joins the partition 8 near its lower edge and extends therefrom toward the end wall 4 in a plane parallel to the plate 9. The ends of the plates 9 and 10 are joined by a plate 11 of like width. The partition or wall 8, the plates 9, 10, and 11 and the front and rear walls 5 and 6, respectively, comprise the walls of the oven A.

In the upper portion of the space provided between the wall 3 and partition 8, and supported upon flanges 12 and 13 which are secured to said wall and partition directly opposite each other, is the grate 14, above which is located the combustion chamber B for solid fuel, said chamber being

provided with the usual liner 15, of fire brick or other such material. Beneath the grate 14 is the ash pit C.

A flue E is provided for the stove by the 5 L-shaped shell 20, which is secured to the rear wall 6 of the casing. The lower end of this flue communicates, through a hole 21 in said wall, with the space beneath the plate 10, and this space communicates with the 10 combustion chamber B through a passageway D produced by the spacing of the plate 11 from the wall 4 and the plate 9 from the top plate 7. Thus it will be seen that the 15 products of combustion from the chamber B are entrained about the walls of the oven A through the passageway D before they escape to the flue E. This is in accordance with the practice usually followed in the 20 construction of solid fuel stoves, and it will be seen from the construction illustrated in the drawings that there is nothing to hinder in the slightest degree the operation of my stove as a stove of this type.

An angular trough-shaped casing 25 is 25 secured to the underneath surface of the top plate 7 and extends across its right hand end and along a portion of its front. Within this casing are contained the gas burners 26 for the top of the stove. These burners 30 receive gas from the supply pipe 27 through tubes 28, mixers 29, and valves 30. A plate 31, which corresponds in shape to the casing 25, rests therein just above the upper surface of the burners 26 and is provided with an 35 opening 32 for each of the burners 26, the opening being of substantially the same shape as the burner. An upwardly extending flange 33 which surrounds the plate 31 bears upon the inner surface of the casing 40 25 to retain the plate in position.

The front wall of the casing 25 is slotted to accommodate the tubes 28 and to provide an air supply for the burners 26. An extension 25^a, which is carried by the inner 45 wall of the casing 25, provides an auxiliary flue which has communication with the interior of the casing through openings 25^b. The majority of the openings 25^b are in proximity to the burners farthest removed 50 from the exit end of the casing 25. The auxiliary flue and the interior of the casing 25 communicate directly with the flue e (which is provided by the horizontal arm 35 of the shell 20) through a hole 34 in the 55 rear wall 6 of the stove; and by reason of the arrangement above described, a part of the products of combustion from the front burners escape through the auxiliary flue to the flue e, and the draft created by these 60 burners is thus prevented from interfering with the efficiency of the rear burner. A damper 36 may be hinged within the flue e to close it off from the main flue E when the stove is being heated by solid fuel.

65 A wall or partition 37, which is spaced

laterally from the partition 8, extends upwardly from the bottom plate or wall 2 to about the plane of the oven bottom where it turns toward the said partition and joins it above an elongated opening or slot 38 70 formed therethrough above the plate 10 which forms the bottom wall of the oven. This slot 38 extends substantially the full width of the partition 8. Supported within the combustion chamber F thus formed is a 75 gas burner 40, having connection with the gas supply pipe 41 through the tube 42, mixer 43, and valve 44.

Openings 45, which are formed in the bottom plate 2 of the stove casing, are controlled by dampers 46. These dampers are in the form of cover plates or doors, and are provided with lugs 47 which overhang one of their edges. The squared shaft 48 passes through correspondingly shaped 80 holes in the ears 47 and is journaled at its rear end in a lug 49 which projects upwardly from the plate 2. Upon the forward end of this shaft is secured a cam plate 50 which is adapted to coöperate with a finger 90 51 secured to the lower end of the valve stem 52 of the valve 44. The cam 50 is of a shape that will cause a partial rotation of the squared shaft 48 when the said cam is actuated by the finger 51. From the construction of these parts, it will be seen that I automatically supply the required quantity of air to the oven burner simultaneously with the operation of the valve which supplies the gas thereto.

Diagonally opposite that corner of the oven which is provided with the slot 38 is a plate 60, which extends from the plate 9 to the plate 11 substantially at an angle of 45° and from the front wall to the rear wall 105 of the oven. Between said plate 60 and the corner of the plates 9 and 11 is a flue G, which communicates at its rear end with the flue e through a triangular hole 61 in the wall 6. The central portion of the plate 60 is cut away in order that the interior of the oven may have communication with the flue G, and the opening thus formed between the oven and the flue is adapted to be closed by a slide damper 62 which has 110 holes 63 adapted to register with holes 64 in a stationary plate 65. The plate 62 is movably attached to the plate 65 by screws 66 which project from the latter through slots 67 in the plate 62.

Pivoted at 68 to the plate 11, a short distance below the central portion of the plate 62, is a lever 69, which is bent outwardly at its upper end to conform to the inclination of the plate 60 and which terminates in a fork which embraces a pin 70 located at the center of the plate 62. The lower end of the lever 69 is curved rearwardly and enlarged to provide a weight 71.

Carried by the partition 8 and extending 130

horizontally throughout its width is a ledge 72. A similar ledge 73 is carried by the plate 11 directly opposite the ledge 72. Channels 74 which are carried by the vertical extensions 75 of a deflector member or plate 77 are adapted to be supported upon the ledges 72 and 73. The deflector plate 77 is coextensive with the bottom of the oven and its front and rear edges are turned down a sufficient distance to engage the plate 10 and support the deflector plate in a transverse direction. A fin 76 is carried by and above that channel 74 which embraces the ledge 73 for a purpose which will be mentioned hereinafter. The central portion of the plate 77 is cut away to provide an opening 78 therethrough, and a part of the material cut from said opening is turned downwardly to meet the surface of the plate 10, as shown at 79. Surmounting the plate 77 is a baffle plate 80 which is spaced from the former plate, by its downturned ends 81, approximately the same distance as the plate 77 is elevated above the oven bottom. This plate 80 extends substantially from the front to the rear of the deflector plate 77, but is somewhat narrower in order to provide an unobstructed passage for the products of combustion which are directed from the burner 40 about its edges through the passageway *a* beneath the plate 80, the holes 78, and the passageway *a'* beneath the deflector plate 77. The weight 71 on the lower end of the lever 69 (which has been previously mentioned) normally hangs a slight distance below the ledge 73, and is adapted to be engaged by the fin 76 and swung upon its pivot 68 to move the slide damper 62 into open position as the deflector is inserted into the oven. When the deflector is in place, the weight 71 rests upon the upper surface of the fin 76 and retains the slide damper 62 in its open position. This provides an escape for the products of combustion which were introduced into the oven in the manner previously set forth. In the absence of the deflector, the ledges 72 and 73 support the shelf which is indicated in the drawing by dotted lines, as resting upon the upper flanges of the channels 74.

In Fig. 7 I have shown an alternative form of damper for controlling the supply of air to the burner or combustion chamber F which comprises a slide plate 85 having holes 86 throughout its length, which are adapted to be brought into register with holes 87 in the bottom plate or wall 2 of the stove casing when movement of the plate is effected by the operation of the valve 44^a, the stem of said valve having connection with the slide plate 85 through a finger 51^a which is provided near its end with a pin which occupies the transverse slot 88 in the end of the slide plate.

66 The oven A, the combustion chamber B,

and the ash pit C may be provided with suitable doors which may be hinged to the front wall 5 of the stove casing in the usual manner, the door for the oven being shown at 9 in Fig. 2.

From the foregoing description, it will be seen that I provide a cooking and baking stove or range in which either solid fuel, such as coal, or gas may be used as the heat-producing medium; one which will operate 75 as well with one form of fuel as the other, and which may be converted from a solid fuel stove to a gas stove by simply inserting a member or deflector into the bottom portion of the oven. This operation, it will be 80 remembered, automatically opens the damper which provides a vent for the oven, and the turning on of the gas for the oven burner opens the damper which supplies air to said burner in the desired quantity to promote 85 proper combustion, and to the oven to create a proper circulation therethrough. A greater quantity of air than that required for the amount of gas being used would unduly lower the temperature of the oven and result in an extravagance of gas. When it is desired to burn coal or wood in the stove, the member or deflector is removed from the oven, the weighted lever 69 swings to its normal position and shifts the damper plate 95 62 to its closed position, and since the damper in the bottom of the burner chamber F is closed when the gas valve is turned off, the stove is in readiness for operation.

Having thus described my invention, what I claim is:—

1. A stove comprising a casing having end, front and rear walls and top and bottom plates, and inclosing an oven, and a combustion chamber and ash pit at one side thereof and a passageway extending across the top, down the opposite side and underneath the oven, the front and rear walls of the casing forming the corresponding walls of the oven, an L-shaped shell secured to the rear wall, one arm of which provides a flue for the passageway beneath the oven, a trough-shaped casing secured to the underneath surface of the top plate, the interior of which communicates with the flue in the other arm of the aforesaid shell and having burners therein, a chamber at that side of the oven adjacent the ash pit and communicating with the oven through an opening in its side wall, a burner within said chamber, a flue for the oven communicating with the last mentioned flue, and a deflector in the oven above the aforesaid opening.

2. A stove comprising a casing having end, front and rear walls and top and bottom plates and inclosing an oven, and a combustion chamber and ash pit at one side thereof and a passageway extending across the top, down the opposite side and underneath the oven, the front and rear walls of

the casing forming the corresponding walls of the oven, a chamber at that side of the oven adjacent the ash pit and communicating with the oven through an opening in its side wall, the bottom of the chamber being formed by the bottom plate of the stove casing and said plate having holes for the admission of air to said chamber, a burner within said chamber having a valve, a 10 damper for said holes, and a flue for the oven located diagonally opposite the aforesaid opening.

3. A stove comprising a casing inclosing an oven, a combustion chamber, an ash pit 15 and a passageway which extends across the top, down one side and underneath the oven, the front and rear walls of the casing forming the corresponding walls of the oven, a flue for the passageway beneath the oven, a 20 chamber at that side of the oven opposite the side down which the passageway extends and communicating with the oven through an opening in its side wall, holes for the admission of air to said chamber, a burner 25 within said chamber having a valve, a damper for said holes, a flue for the oven, a deflector in the oven above the aforesaid opening and comprising a plate which is coextensive with the bottom of the oven and 30 spaced thereabove by its downturned ends, there being an opening in the central portion of the plate, a second plate surmounting the first mentioned plate and extending from the front to the rear thereof, but stopping 35 short of its lateral edges, whereby the products of combustion from the oven burner are directed beneath the first mentioned plate and through the opening therein, beneath the second mentioned plate and around its 40 lateral edges to the upper portion of the oven, from whence they are permitted to escape through the oven flue.

4. The combination with a coal range, of a wall arranged in the ash pit and forming 45 a chamber extending from the front to the rear beside the oven, the oven wall adjacent to said chamber having an elongated opening therethrough placing said chamber in communication with the interior of the oven, 50 a burner in said chamber, and a member extending across the oven just above said opening.

5. The combination with a coal range, of a partition extending laterally and down- 55 wardly in the ash pit from the lower portion of the oven wall to the bottom wall of the range to form a combustion chamber at the adjacent lower corner of the oven, the

oven wall having an elongated opening therethrough at the top of said chamber, a 60 burner in said chamber, and a member extending across the oven above said opening and adapted to direct the combustion gases along the bottom of the oven.

6. The combination with a coal range, of a 65 chamber formed by partitioning off the lower inner corner of the ash pit, the adjacent wall of the oven having an elongated opening therethrough into the upper end of said chamber, a burner in said chamber, and 70 means for causing hot combustion gases from said chamber to flow into the oven and across the bottom thereof to points remote from said opening.

7. The combination with a coal range, of 75 a combustion chamber formed out of the lower corner of the ash pit adjacent to the oven, there being an opening leading from the upper portion of the chamber into the oven just above the oven bottom, and a plate 80 supported within the oven so as to lie in a plane just above the top of said opening, said plate extending almost entirely across the oven so as to direct the hot gases from said chamber along the bottom of the oven 85 before they rise.

8. The combination with a coal range, of a combustion chamber formed out of the lower corner of the ash pit adjacent to the oven, there being an opening leading from the 90 upper portion of the chamber into the oven just above the bottom of the oven, and means arranged within the oven for causing the combustion gases entering the oven through said opening to flow along the bottom of the 95 oven to the sides thereof before rising toward the top of the oven.

9. In a combined coal and gas range, an oven having an elongated opening extending through the wall into the ash pit adjacent to 100 the bottom of the oven, an outwardly and downwardly curved wall extending from the top of said opening to the bottom of the ash pit and forming a combustion chamber, and means arranged within the oven for causing the combustion gases entering the oven through said opening to flow along the bottom of the 105 oven to the sides thereof before rising toward the top of the oven.

In testimony whereof, I hereunto affix my 110 signature in the presence of two witnesses.

FRANK A. NIEBERDING.
